CLAIM

The ornamental design for an automobile body part—spider, as shown and described.

DESCRIPTION

FIG. 1 is a front, top perspective view of an automobile body part—spider of our present design;

FIG. 2 is a left side view thereof;

FIG. 3 is a right side view thereof;

FIG. 4 is a top view thereof; and,

FIG. 5 is a top, left perspective view thereof.

The broken lines depict a portion of the automobile body part—spider that forms no part of the claimed design.

1 Claim, 5 Drawing Sheets
